3 Claims. (Cl. 105—280)

My invention relates to railway cars and more particularly to improvements in doors and in mechanism for supporting the doors of railway hopper cars in closed position.

The principal object of the invention is to provide improved means for supporting a plurality of hopper car doors in closed position.

A primary feature of the invention consists in providing a pair of oppositely arranged hinged doors which are successively movable toward closed position in a predetermined order and in associating with one of the doors means for supporting it in a partially closed position and in associating with the other door means for supporting it in fully closed position, the second named door having a portion at its free edge adapted to extend beneath the free edge of the first named door so that, when the second door is moved to fully closed position, the first named door is caused to move therewith to a corresponding position of closure and to be retained thereby in the latter position.

Another feature of the invention consists in providing a railway car having a pair of oppositely arranged hinged doors for closing the lading discharge opening with a pivoted hook for supporting one of the doors in a partially closed position and with a second pivoted hook for supporting the other door in partially closed and in fully closed positions, the second named door having a portion at its free edge adapted to extend beneath the first named door so that, when the second named door is moved from partially closed to fully closed position, the first named door is caused to move therewith to fully closed position and to be retained thereby in the latter position.

Other and more specific features of the invention, residing in advantageous forms, combinations and relations of parts, will hereinafter appear and be pointed out in the claims.

In the drawings, illustrating a preferred embodiment of the invention,

Figure 1 is a side elevational view of the lower portion of a hopper of a railway car illustrating the door arrangement and the door supporting mechanism, the doors being shown as supported in fully closed position.

Figure 2 is a view similar to Figure 1 but showing both of the doors supported in partial positions of closure.

Figure 3 is a detail view of the cover plate of the door supporting mechanism.

Figures 4 and 5 are sectional views taken on lines 4—4 and 5—5, respectively, of Figure 3.

Figure 6 is an end elevational view of the hopper construction illustrated in Figure 1.

Figure 7 is a longitudinal sectional view taken on line 7—7 of Figure 6.

Figure 8 is a transverse sectional view taken on line 8—8 of Figure 1.

The hopper car chosen for purposes of illustrating the invention is of the type wherein the hoppers extend downwardly in pairs on opposite sides of the center sill of the car.

Referring more particularly to the drawings, 1 indicates one of the car hoppers which is formed of inner and outer side sheets 2 and 3, respectively, and slope sheets 4. Rigidly attached to the lower end of the hopper sheets is a door frame 5 having an opening through which lading within the car is adapted to discharge by gravity. The door frame is preferably connected by a bracket 15 to the car center sill 16 and it may be advantageously formed as an integral casting having inner and outer preferably vertical side walls 6 and 7, respectively, which incline inwardly adjacent their lower edges and terminate in sealing flanges 8. The side walls 15 of the door frame are integrally connected by hinge butt portions 9, each of which is formed with two pairs of hinge lugs 10. Depending from the lower portion of each hinge butt of the frame is a sealing flange 11 integrally connecting the side sealing flanges 8 of the frame. The outer ends of the sealing flanges 8 along opposite sides of the door frame incline downwardly from the hinge butt portions of the frame so that, instead of being disposed in a single plane, the outer edges of the marginal flanges are disposed in two downwardly converging planes.

Associated with the door frame are a pair of oppositely hinged doors 12 and 13 which, when in closed position, are respectively disposed in downwardly converging planes. The doors are movable to open position under the influence of gravity and each is provided with a pair of hinge arms 14 which are pivotally connected at their outer ends to the adjacent hinge lugs 10.

Door 12 is formed with marginal flanges 17, the marginal flange at the hinge end of the door preferably terminating in a lateral extension 18 and door 13 is provided with marginal flanges 19, each of which has a lateral extension 20. The portion of door 12 adjacent its free edge is adapted to project into and be received by the free edge portion of the door 13 so that, when the doors are disposed in closed position, door 13 underlaps door 12 with the marginal flange at the free edge of door 13 in engagement with the outer face of

the main body portion of door 12 and with the flange at the free edge of door 12 in engagement with the inner face of the main body portion of door 13. Door 13 is of slightly greater width than door 12 so that, when the doors are in closed position, the portions of the side marginal flanges of door 13 adjacent the free edge of the door will, as shown in Figure 8, overlap the outer faces of corresponding portions of the side marginal flanges of door 12 and, in order that the portion of door 12 which is adapted to be interposed between door 13 and the door frame will not prevent door 13 from assuming a completely closed position, the lower edges of the sealing flanges of the frame may be notched out as indicated at 21 and clearly shown in Figure 7.

Rigidly secured to the outer face of door 13 is an angularly shaped member 22 commonly known as a door spreader which extends beneath the center sill for attachment to a corresponding door (not shown) of the hopper (not shown) disposed on the opposite side of the center sill 16 so that the corresponding doors of the two hoppers may swing as one. Door 12 is likewise provided with a door spreader 23 which, as will hereinafter appear, need not be of as heavy a section as door spreader 22.

The mechanism for supporting the doors includes two pivotally mounted hooks 24 and 25, respectively. Hook 24 is arranged to cooperate with door 12 and it is formed with a ledge or shoulder 26 adapted to engage flange 27 of door spreader 23 to support door 12 in partially closed position as shown in Figure 2. Hook 25 is adapted to cooperate with door 13 and it is formed with two ledges or shoulders 28 and 29, respectively, for cooperating with a flange 30 of a door arm 31 which is secured to the door spreader 22 and, in effect, forms a continuation thereof. When shoulder 28 of hook 25 is in engagement with flange 30 of the door arm, door 13 is supported in a partially closed position as shown in Figure 2, and when shoulder 28 of the hook is in engagement with the door arm flange 30, door 13 will be supported in fully closed position as shown in Figure 1.

Not only does hook 25 function to support door 13 in fully closed position but it also functions indirectly to maintain door 12 in fully closed position because the free edge portion of door 12, which door is always moved toward closed position before door 13, is disposed in the path of closing movement of door 13 and, therefore, as door 13 is caused to approach fully closed position it engages door 12 and, lifting it from its hook 24, moves it to fully closed position, in which position it is retained by door 13 and hook 25.

To obtain a mechanical advantage enabling the doors to be easily moved to fully closed position, a fulcrum is preferably provided for receiving a removable door prying lever (not shown). This fulcrum may be conveniently formed by providing a cover plate 32 which is arranged in overlapping relation with the outer faces of the hooks 24 and 25 with a laterally projecting portion 33 having an aperture 34 for receiving the removable lever (not shown), the laterally projecting portion 33 preferably being rigidified around the lever receiving aperture by oppositely projecting ribs or flanges 35. With a fulcrum of this character for receiving a removable lever, sufficient leverage may be obtained for easily moving both doors 12 and 13 from their partially closed positions shown in Figure 2 to their fully closed po-

sitions shown in Figure 1, where they are supported by the hook 25.

Both of the hooks are preferably mounted to pivot about a common axis and, in order that the shouldered portions of the two hooks may move in substantially the same plane, the upper end of hook 24 is laterally offset as indicated at 36 from the lower portion of the hook. The hooks may be conveniently mounted on a cylindrical boss 37 which is integral with and projects inwardly from the inner face of the cover plate 32 and which, together with other similar bosses 38, 39 and 40, constitutes spacers for maintaining the cover plate in spaced relation to the adjacent vertical wall 7 of the door frame. Each of the cylindrical bosses are apertured to receive rivets 41 by which the cover plate is firmly secured to the door frame and boss 38 affords a pivotal support for a cam 42 by which hook 25 may be securely locked in door supporting position. The cover plate 32 is also preferably integrally provided with inwardly projecting lugs 43 and 44 for respectively cooperating with hooks 24 and 25 to limit their pivotal movements toward each other.

The door arm 31 may be of the type which is capable of being adjustably secured to the door spreader so that the hook engaging flange 30 thereof may be disposed in such a position that, when engaged by the shoulder 29 of the hook, the door will be supported in the desired position of complete closure. The adjustment of the door arm is effected by first rotatably securing it to the spreader 22 by a rivet 45 and then, after adjusting the arm to the position desired, an additional rivet 46 is driven through that one of the plurality of apertures 47 formed in the inner end of the door arm which most nearly coincides with one of the plurality of apertures 48 formed in the spreader. The apertures in the spreader are, of course, spaced a greater distance apart than the apertures in the door arm so that, by rotating the door arm about the rivet 45 through a limited arc, different ones of the two sets of apertures are successively brought into registry. With four apertures in the door arm, it will, of course, be appreciated that the arm may be secured to the spreader in any one of four different positions of adjustment.

To open the doors and permit the lading to discharge from the hopper, the locking cam 42 is first rotated in a clockwise direction from the position shown in Figure 1 to the position shown in Figure 2. Hook 25 is then knocked from engagement with the flange 30 of door arm 31, thus releasing door 13 and permitting it to swing to open position under the influence of gravity. Door 12, which was retained in fully closed position by door 13, moves downwardly only a short distance upon the release of door 13 unless hook 24 is held up out of the path of downward movement of the projecting end of the door spreader 23. Should downward movement of door 12 be arrested by hook 24, it will, of course, be necessary to knock the hook out of engagement with the spreader to enable the door to swing fully open.

In closing the hopper, door 12 is first moved toward closed position. It is swung up and supported in a partially closed position by hook 24. Door 13 is then swung up and supported in a partially closed position by shoulder 28 of hook 25. Door 13 is then moved (by the removable prying lever if desired) toward fully closed position. By reason of the overlapping engagement of the free edges of the two doors, door 12 is car-

ried upwardly out of engagement with hook 24 by door 13 until they both assume fully closed position, where they are retained by shoulder 29 of hook 25 engaging the cooperating door arm.

This application is a substitute for my abandoned application Serial No. 401,007, filed July 3, 1941.

While I have illustrated and described the preferred embodiment of my invention, those skilled in the art will appreciate that various modifications and alterations may be made in detail features thereof without departing from the spirit and scope of the invention as defined in the appended claims.

What I claim is:

1. In a railway car having a lading discharge opening, a pair of oppositely arranged hinged doors respectively adapted to be disposed in downwardly converging planes for closing said lading discharge opening, each of said doors having a main body portion and upturned marginal flanges along the side and free edges thereof, means for supporting one of said doors in a partially closed position, and means engageable with the other door for supporting both of said doors in fully closed position, said marginal flanges of the doors being arranged so that when the doors are in fully closed position the portions of the side marginal flanges adjacent the free edges of the doors are in overlapping relation and the marginal flanges at the free edge of each door overlaps the body portion of the other door.

2. In a railway car having a lading discharge opening, the combination with a pair of oppositely arranged hinged doors for closing said opening, said doors being movable to open position under the influence of gravity and being successively movable toward closed position in a predetermined order, one of said doors being of

greater width than the other and each being provided with marginal flanges, of means for supporting the door of less width in a partially closed position, and means for supporting the door of greatest width in fully closed position, the portions of the side marginal flanges adjacent the free edge of the door of greatest width being adapted to overlap corresponding portions of the outer faces of the side marginal flanges of the other door and the marginal flange at the free edge of the door of greatest width being adapted to extend beneath the other door whereby when the door of greatest width is moved to fully closed position the other door is caused to move therewith to a corresponding position of closure and to be retained thereby in the latter position.

3. A railway car having a hopper, a door frame rigid with the hopper having a lading discharge opening, downwardly extending sealing flanges surrounding said opening, a pair of doors hingedly mounted adjacent opposite sides of the frame for closing said opening, each of said doors having upturned marginal flanges along its side and hinged edges for cooperating with said sealing flanges to prevent the escape of lading from the hopper, one door also having an upturned marginal flange along its free edge adapted to overlap the body portion of the other door for preventing the escape of lading from the hopper between the doors, and one of said doors being narrower than the other adjacent its free edge so that portions of the side marginal flanges adjoining the free edges of the doors are adapted to overlap each other, means for supporting one of said doors in a partially closed position, and means engageable with the other door for supporting both of the doors in a fully closed position.

ERNEST G. GOODWIN.
